CONCRETE INSERT

John H. Phillips, Chicago, Ill.

Application July 2, 1936, Serial No. 88,602

4 Claims. (Cl. 72—105)

The invention relates to devices commonly called concrete inserts for concrete walls, beams and ceilings, the devices being adapted to be exactly positioned on and fastened to forms before the concrete is poured and upon removal of the forms provide exposed portions suitable for fastening mechanisms and apparatus of various kinds thereto.

Devices of the character described have heretofore been constructed as a unitary member comprising an elongated body or stem providing a nailing flange on one end by means of which it is fastened to a form before the reinforcing steel is placed, with the result that many of them are misplaced during the setting of the steel. Such devices are frequently located in narrow or otherwise constricted spaces and this, as well as considerations of economy, make it necessary that the entire device, including the flange, be relatively narrow. It is frequently desirable that the devices be positioned exactly perpendicular to or at some definite selected inclination to the face of the wall or beam in which the devices are embedded. The fastening of an elongated unitary device to a form by driving nails through an end flange is obviously difficult and is also time consuming. In many instances, a plurality of such devices are provided as a support for a single apparatus thereby making it necessary that the devices be accurately spaced and aligned. The location of the devices is indicated by marking the form in any suitable manner and exact spacing of the device requires that the individual devices be exactly positioned over the marks indicating their location. Obviously, the exact centering of an elongated unitary device over such a mark is also difficult and time consuming, particularly with devices not having a continuous longitudinal bore.

The above described difficulties inherent in exactly locating unitary inserts on forms of concrete or similar structures are eliminated by providing an insert device consisting of a centrally apertured flange member adapted to be exactly positioned and securely fastened to the form before reinforcing steel is set, and a hollow elongated stem or body member adapted to be attached to the flange member after the reinforcing steel is set and before the concrete is poured, and upon removal of the forms to provide an exposed portion suitable for fastening mechanisms and apparatus of various kinds thereto. The aperture in the flange member adapts it to be quickly and accurately located on any selected point of the form and since it is shallow, it may

be quickly and easily fastened to the form and offers no obstacles to the placing of the reinforcement. The flange is preferably constructed of non-corrosive metal and the stem or body portion may be constructed of steel or other material providing the requisite strength and of relatively small diameter or lateral dimensions such that it does not interfere with the placing of the reinforcing steel.

It is an object of the invention to provide insert devices as an assembly of two members of the kind described whereby such devices are adapted to be located with exactness and facility in any selected position on a form and may be quickly and easily fastened to the form by the use of any ordinary tool such as a hammer.

Another object of the invention is the provision of improved insert devices of the kind described which are adapted to be mounted on a form without interfering with the placing of reinforcing material.

A further object of the invention is the provision of a device of the kind described which is inexpensive to manufacture, durable, simple in construction and satisfactory for its intended purpose.

Many other objects and advantages of the construction herein shown and described will be obvious to those skilled in the art from the description herein given.

To this end my invention consists in the novel construction, arrangement and combination of parts herein shown and described and more particularly pointed out in the claims.

Referring to the drawing, wherein like reference characters indicate like or corresponding parts:

Fig. 1 is a sectional view of a fragmentary portion of a reinforced concrete beam or ceiling wall showing the assembled device as embedded in the concrete and fastened to a form;

Fig. 2 is a longitudinal sectional view showing the device as comprising a main body portion and a separable flange member arranged in slightly spaced-apart disassembled relation; and

Fig. 3 is a plan view of the flange member. Referring now more particularly to the drawing, the device comprises a main body portion consisting of a rod or bar 10 and a separable flange member 11. The member 11 has a circular nailing flange 12 providing a plurality of holes 13 arranged in circumferentially spaced-apart relation through which nails 14 are adapted to be driven to fasten the member to a form 15 before mounting the bar 10 thereon.

The member 11 has a central aperture 16, preferably frusto-conical, and is thereby adapted to receive the adjacent end of the rod 10 which is tapered to closely fit therein. The member 11 5 may be exactly located in any predetermined position on the form indicated by a suitable mark or otherwise since the mark can be observed through the aperture 16. In the event the member 11 happens to be centered over the contiguous 10 edges of adjacent boards comprising the form 15, the member may be shifted circumferentially so that all of the holes 13 are spaced apart from the contiguous edges of the form boards.

The thickness of the flange 12 is such that it 15 does not interfere with overlying reinforcement and the depth of the member 11 is such that it can be nailed or otherwise fastened to the form 15 with facility. The rod 10 is firmly anchored 20 in the concrete by providing it with a head 17 which may be formed integrally with the rod but is shown in the drawing as comprising a standard nut since the latter is less expensive. A close 25 binding fit of the rod 10 in the aperture 16 is secured by merely striking the head 17 or the adjacent end of the rod with a hammer after the member 11 is nailed to the form.

The rod 10 is provided with a threaded axial bore 18 open at the tapered end of the rod for the reception of bolts, rods or any member forming 30 a connection and support for apparatus to be suspended from or supported by the concrete structure upon removal of the form 15. The exposed face of the member 11 coincides with the surface of the wall and upon removal of the forms 35 15 and cutting of the nails 14 permits a close fit of the apparatus or mechanism with the structure.

Thus it will be seen that I have provided a novel 40 and improved insert device comprising an assembly of two members, one being a flanged member adapted to be exactly positioned on and nailed to the form before the device is assembled whereby the nailing operation is accomplished with facility, and the other being an elongated interiorly threaded hollow member adapted to be quickly 45 and easily mounted on the flanged member in exact perpendicularity or at any other requisite angle to the surface of the structure bounded by the form after reinforcement is placed 50 therein.

Having thus described my invention, it is obvious that various immaterial modifications may be made in the same without departing from the spirit of my invention; hence I do not wish to be 55 understood as limiting myself to the exact form, construction, arrangement, and combination of parts herein shown and described or uses mentioned.

What I claim as new and desire to secure by Letters Patent is:

1. An insert device of the kind described for concrete and similar structures comprising an assembly of two cooperating members, one of said members being shallow and providing means for fastening it to a form prior to assembly, the other of said members being elongated and having a threaded bore open at one end, said shallow member having a central aperture convergent toward the form and said elongated member having its open end bounded by a tapered surface adapted to closely fit in said aperture when the members are assembled. 10

2. An insert device of the kind described comprising a pair of members adapted to be assembled in cooperative relation, one of said members being elongated and having a threaded bore open at one end and the other of said members being shallow and providing means adapting it to be fastened to a form and providing a central aperture, one of the said members providing an outer bounding surface convergent towards the other, said other of the said members providing an inner bounding surface similarly convergent toward the other member to provide a close fitting seat for said convergent bounding surface when the members are assembled with said bores and apertures in axial alignment. 15

3. An insert device of the kind described for concrete and similar structures comprising a pair of members adapted to be assembled in cooperative relation, one of said members being elongated and having a threaded bore open at one end, the other of said members having one end 35 forming a flange suitably apertured for nailing it to a form prior to assembly and providing a bore convergent towards its flanged end, the open end of the elongated member being similarly tapered and adapted thereby to closely fit within 40 the convergent bore of the flanged member. 45

4. In an insert device of the kind described, an assembly of two members, one member having one end forming a flange suitably apertured for nailing to a form and providing an axial bore, the other of said members providing an elongated bore open at the end adjacent the flanged member, one of said members providing a bounding surface convergent towards the other, the other of said members providing a bounding surface 50 similarly divergent towards the other to provide a close fitting seat for said convergent bounding surface when the members are assembled with said bores in axial alignment. 55

JOHN H. PHILLIPS.
